(57) **CLAIM**

The ornamental design for a belt buckle, as shown and described.

DESCRIPTION

FIG. 1 is a front, right and bottom perspective view of a belt buckle, showing my new design;

FIG. 2 is a rear and right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the belt buckle in an open status.

The broken lines shown in the drawings illustrate portions of the belt buckle that form no part of the claimed design.

1 Claim, 9 Drawing Sheets
